GOLF BAG CARRIER

Filed July 6, 1937

Fig. 1.

UNITED STATES PATENT OFFICE

2,124,265

GOLF BAG CARRIER

Clarence C. Sinnott, San Clemente, Calif.

Application July 6, 1937, Serial No. 152,163

6 Claims. (Cl. 280—40)

This invention relates to a golf bag carrier.

An object of the invention is the construction of a simple and efficient wheeled carrier, whereby the golf bag and golf sticks can be easily transported by the operator.

Another object of the invention is the construction of a simple and efficient wheeled carrier, which will receive a golf bag of any standard type.

10 A still further object of the invention is the construction of a novel golf bag carrier, which by reason of its foldable or collapsible parts, can be closed up so as to occupy a relatively small amount of space when not in use.

15 Another object of the invention is the construction of a golf bag carrier which can be folded or closed by reason of jointed or hinged parts, and which, when the operator desires, can be quickly unfolded or extended, to place the carrier in an efficient and operative condition.

20 With the foregoing and other objects in view, my invention comprises certain novel constructions, combinations, and arrangements of parts as will be hereinafter fully described, illustrated in the accompanying drawing, and more particularly pointed out in the appended claims.

In the drawing:

Figure 1 is a view in front elevation of a golf bag carrier constructed in accordance with the present invention.

25 Figure 2 is a view in side elevation of the golf bag carrier, showing the same in a reclining or "at rest" position.

Figure 3 is a horizontal, sectional view taken on line 3—3, Figure 1, and looking in the direction of the arrows.

30 Figure 4 is an enlarged, fragmentary view of the sectional axle, showing in dotted lines the same in a folded position.

Figure 5 is a view similar to Figure 4 looking at the bottom of the axle.

35 Figure 6 is a fragmentary view of the base plate, looking at the bottom thereof, and showing the angle rest in an extended or operative position.

Figure 7 is an enlarged sectional view taken on line 7—7, Figure 1, and looking in the direction of the arrows.

40 Figure 8 is a view in side elevation of another embodiment of the invention, showing a different type of a handle.

The purpose of this golf bag carrier is to furnish golfers with an inanimate caddy, easily pulled along the course, which will relieve a person of the fatigue of carrying his own clubs, and when the carrier is stationary, the bag resting thereon will be in a handy position for replacing and obtaining clubs.

45 The carrier will also be of particular value to elderly people, and people in poor health, and

those physically weak, to whom the carrying of a bag filled with clubs means the spoiling to a great extent of the pleasure of the game. The invention will also relieve the situation in case there is a scarcity of caddies.

In carrying out the invention, and referring specifically to the drawing, designates a sectional axle to which is secured a base plate 2. On base plate 2 is suitably secured a bag-holding flange 3, which in the present instance is annular, 10 in shape, and angular in cross section. A flat bar-like upright 4 is provided at its lower end with a right angled extension 5, which extension is fixedly secured preferably to the bottom of the plate, as clearly seen in Figure 2. This upright 15 4 is provided preferably near its upper end with a ratchet slot 6, in which slot are formed upwardly-extending teeth 7 and downwardly-extending teeth 8, for the purpose hereinafter described. On the upper end of the upright 4 is secured a horizontal handle 9; this handle has grips 10 on its outer ends. An integral or fixed loop 11 is formed on the inner face of upright 4, near the handle 9. The golf bag 12 is placed, at its bottom, within flange 3, and strap 13 is threaded through loop 11, for securely holding the bag in position upon the carrier. The golf bag 12 is provided with the usual grip strap 14.

The sectional axle 1 comprises a central portion to which plate 2 is securely fastened. At each end of the central portion of the axle is an intermediate section 15 and an outer section 16. Each intermediate section 15 is connected by a hinge 17 to one end of the central section of the axle, and each outer section 16 is connected by hinge 18 to the outer end of an intermediate section. A plate 19, extending longitudinally of the axle, is fixedly secured by rivets 20 to the intermediate section 15, the outer free end of plate 19 overlapping the hinge 17 so as to limit the downward swinging movement of the intermediate section, beyond a horizontal plane, or true alignment with the central portion of the axle. The outer section 16 is provided with an integral depending stop 21 which is close to the hinge 18 and acts to prevent outer section 16 from swinging downwardly below a horizontal position when the carrier is folded, as clearly seen in Fig. 4.

The outer section 16 is retained in a true horizontal or operative position by means of bowed spring 22; this spring being secured by rivet 23, at its inner end, to the inverted V-shaped brace 24, the outer end of spring 22 pressing at all times upon the outer section 16. In other words, the joints of these sections can be "broken" when the operator desires, for folding up the carrier, but they can be also acted upon, by manual pressure, to cause the sections of the axle 1 to assume their true aligned horizontal

position in operation. On each outer section 16 is a wheel 25 of any suitable construction.

The inverted V-shaped brace 24 has its outer ends pivotally connected at 26 to lugs 27, which 5 lugs 27 are integral with the intermediate sections of axle 1, close to the hinges 18. The upper end of the inverted V-shaped brace 24 is suitably mounted in the ratchet locking pin 28. This pin 28 extends through ratchet slot 6. Locking 10 pin 28 is provided on its inner end with an integral washer 29 (Fig. 7) and on its outer end with an integral head 30; this head 30 serves as a grip, whereby the operator can easily grasp the pin for adjusting the same in the ratchet 15 slot 6.

Upon referring to Figure 1 it will be seen that teeth 7 produce upwardly extending slots into which the locking pin 28 may be positioned, and teeth 8 produce downwardly extending slots for 20 receiving the pin 28. When the carrier is in its normal or working position the parts will be extended as clearly shown in Figure 1, with the locking pin 28 in one of the downwardly-extending slots formed by teeth 8, whereby the hinged 25 sections of the axle are securely held in true alignment. Upon the operator moving pin 28 out of the slot in which it is resting, the pin can be adjusted vertically within the ratchet slot 6, and placed between two of the upwardly extending teeth 7 as indicated in Fig. 1 by dotted lines "A". When in the dotted position "A" the hinged sections of the axle will be held securely in their retracted or folded position, as illustrated by dotted lines in Fig. 1. When the parts are 30 in their folded or closed position the carrier will require a much smaller space for storage in a building, automobile or the like, which is of importance.

The angle foot or rest 31 is pivotally connected 40 at 32 to the bottom of the base plate 2 (Fig. 6) and this rest 31 is provided with a socket 33 that is adapted to receive registering, depending tits 33 formed on the bottom face of base plate 2. Therefore it will be seen that the angle rest 45 31 can be adjusted or swung in an arc of a circle, and retained in its adjusted position by reason of the socket and tit structure; in Fig. 6 the angle rest is shown in adjusted positions by dotted lines "B".

In Figure 8 the structure is the same as in the 50 preferred embodiment, shown in Figures 1 to 7, except that the upright 4a is bent at its upper end to form a suitable handle 9a. Other forms of handles may be formed on the upright without departing from the spirit and scope of this 55 invention.

While I have described the preferred embodiments of the invention and illustrated the same in the accompanying drawing, certain minor 60 changes or alterations may appear to one skilled in the art to which this invention relates during the extensive manufacture of same, and I, therefore, reserve the right to make such changes or alterations as shall fairly fall within the scope of 65 the appended claims.

What I claim is:

1. In a golf bag carrier, the combination of 70 an axle provided with foldable end sections, wheels on said end sections, an upright provided with a ratchet slot and with upwardly-extending teeth and downwardly-extending teeth in said slot, and means connected to said end sections and extending into said ratchet slot and engaging said teeth, whereby when said connecting

means is engaging said downwardly-extending teeth said end sections will be in an extended or normal position and when said connecting means is engaging said upwardly-extending teeth said end sections will be in a raised or folded 5 position.

2. In a golf bag carrier, the combination of a sectional axle provided with a central portion and at each end with an intermediate section and an outer section, means hingedly connecting 10 all of said sections together, golf bag supporting means mounted on said central portion, and means for securing said intermediate sections and outer sections in adjusted positions.

3. In a golf bag carrier, the combination of a 15 sectional axle provided with a central portion and at each end with an intermediate section and an outer section, means hingedly connecting all of said sections and central portion together, golf bag supporting means on said central portion, a bracket connected to said intermediate 20 portions, and means carried by said axle and cooperating with said bracket for holding said bracket in an adjusted position, whereby the sections of the axle are retained in a raised or folded 25 position.

4. In a golf bag carrier, the combination of a sectional axle comprising a central portion, intermediate sections hingedly connected to the ends of said central portion, plates fixedly secured to 30 said intermediate sections and overlapping the hinged connections and extending longitudinally of said sections and said central portion, outer sections hingedly connected at their inner ends to the outer ends of said intermediate sections, 35 each of said outer sections provided at its inner end with a depending integral stop, a bracket pivotally connected to said intermediate sections, springs carried by said bracket and pressing upon said outer sections, and said axle provided with means for holding said bracket in 40 adjusted positions.

5. In a golf bag carrier, the combination of an 45 axle comprising a central portion, intermediate sections pivotally connected to the ends of said central portion, outer sections pivotally connected to the outer ends of said intermediate sections, means on said sections limiting the pivotal movement of said sections, means holding said sections in adjusted positions, and golf bag supporting means carried by said central portion. 50

6. In a golf bag carrier, the combination of a sectional axle comprising a central portion, intermediate sections hingedly connected to the ends of said central portion, plates fixedly secured to the bottom of said intermediate sections and overlapping the hinged connections and extending longitudinally of said sections and central portion, outer sections hingedly connected at their inner ends to the outer ends of said intermediate sections, each of said outer sections provided with a depending stop limiting the pivotal movement of said outer sections upon the intermediate sections, an angular bracket pivotally connected to said intermediate sections 60 near their outer ends, bowed springs secured at their inner end to said angular bracket, the outer ends of said bowed springs pressing downwardly upon said outer sections, said central portion provided with bag holding means, and means 65 carried by said central portion and cooperating with said angular bracket for holding said bracket in different adjusted positions.

CLARENCE C. SINNOTT.
